(57) **CLAIM**

The ornamental design for a fishing reel as shown and described.

DESCRIPTION

FIG. 1 is a front perspective view of a fishing reel showing the new design;

FIG. 2 is a rear perspective view of the fishing reel of FIG. 1 showing the new design;

FIG. 3 is a bottom perspective view of the fishing reel of FIG. 1 showing the new design;

FIG. 4 is a front view of the fishing reel of FIG. 1 showing the new design;

FIG. 5 is a rear view of the fishing reel of FIG. 1 showing the new design;

FIG. 6 is a top plan view of the fishing reel of FIG. 1 showing the new design;

FIG. 7 is a bottom plan view of the fishing reel of FIG. 1 showing the new design;

FIG. 8 is a left side view of the fishing reel of FIG. 1 showing the new design; and,

FIG. 9 is a right side view of the fishing reel of FIG. 1 showing the new design.

The broken lines in the drawings depict portions of the fishing reel that form no part of the claimed design.

1 Claim, 8 Drawing Sheets
